(57) **CLAIM**

The ornamental design for a stand for television receiver, as shown and described.

DESCRIPTION

FIG. 1 is a perspective view of a stand for television receiver showing our new design;

FIG. 2 is a front view thereof;

FIG. 3 is a rear thereof;

FIG. 4 is a left side view thereof where the right side view is a mirror image;

FIG. 5 is a top plan view thereof;

FIG. 6 is a bottom plan view thereof;

FIG. 7 is a rear perspective view thereof;

FIG. 8 is an enlarged view of the left-lower part of the front side thereof; and,

FIG. 9 is a rear perspective view thereof, shown in an environment of use.

The evenly-spaced broken lines in FIG. 9 illustrating a monitor represent environment, while the remaining evenly-spaced broken lines in the drawings illustrate portions of the stand for television receiver that form no part of the claimed design. The dash-dot broken lines in FIG. 8 illustrate the boundary of the enlarged portion of the left-lower part of the front side of the claimed design that form no part thereof.
